UNITED STATES PATENT OFFICE.

JACOB FELBEL, OF NEW YORK, N. Y., ASSIGNOR TO UNION TYPEWRITER COMPANY, OF ILLION, NEW YORK, A CORPORATION OF NEW YORK.

TYPE-WRITING MACHINE.

989,591.

Specification of Letters Patent. Patented Apr. 18, 1911.

Application filed December 8, 1910. Serial No. 596,253

To all whom it may concern:

Be it known that I, JACOB FELBEL, a citizen of the United States, and resident of the borough of Manhattan, city of New York, in the county of New York and State of New York, have invented certain new and useful Improvements in Type-Writing Machines, of which the following is a specification.

- 10 My invention relates to typewriting machines and more particularly to type bar supports or rests, and has for its object the provision of a type bar rest which will tend to absorb the shock of the type bars as they are restored to normal position, thereby reducing or preventing the rebound of the type bars and preventing the adjacent bars from clashing near the type bar support or basket.
- 20 To the above and other ends which will hereinafter appear, my invention consists in the features of construction, arrangements of parts and combinations of devices to be described in the following specification and particularly pointed out in the appended claims.

In the accompanying drawings, wherein like reference characters indicate corresponding parts in the various views, Figure 1 is a fragmentary central vertical sectional view of a typewriting machine embodying my invention. Fig. 2 is a detail plan view of the type bar segment, the type bar rest and its connection with the type bar segment. Fig. 3 is an enlarged detail fragmentary side elevation, partly in section, of one of the devices for connecting a type bar support to the type bar segment. Fig. 4 is a front elevation of the type bar support and the type bar segment to which it is secured, three of the type bars being shown in this view.

The frame of the machine comprises a base 1, corner posts 2 and a top plate 3. The platen 4, diagrammatically shown in Fig. 1, is supported by a carriage on the top plate in the usual manner and is adapted to travel from side to side of the machine. Type bars 5 are pivoted at 6 to a type bar segment 7

and are segmentally arranged and adapted to move upwardly and rearwardly to the printing point. Each type bar is connected to a restoring spring 8 and a forwardly extending link is pivoted to each type bar at 9, the rear end of the link being pivoted at 10 to an upright sub-lever 11 pivoted at 12 to a key lever 13. The key levers are pivoted at 14 to the base of the machine and are provided with finger keys 15 and restoring springs 16. Each of the sub-levers 11 is slotted at its lower end portion as at 17 for coöperation with a fixed fulcrum rod 18 which extends beneath the key levers and is attached at its ends to the base of the machine. The type bar segment is preferably a shifting segment such as that employed in the Monarch machine. Thus each end of the segment is provided with a grooved guide 19 which coöperates with anti-friction balls 20, the latter being likewise received in grooved guides 21 secured to the base of the machine at each side of the segment. Forwardly extending arms or rods 22 project from the type bar segment and each has one member of the universal joint connected thereto at its forward end. In the present instance the universal joints are in the form of ball and socket joints, each socket member being formed by two plates 23 secured together and to the arm 22 which carries it by a bolt 24 which extends through openings in the two members 23 and in the forward end, arm or rod 22 and is secured in place by a nut 24^a. The ball member 25 which coöperates with the associated socket is formed on the rear end of a link 26, the forward end of said link being pivoted to a type rest by a vertically disposed bolt 27 which extends through perforations in rearwardly extending lugs 28 formed on the type bar rest 29. Each nut 24^a connects one end of a leaf spring 30 to the associated socket member of the universal joint, the free end of the spring being bent upwardly and extending beneath the associated link 26 to support the link and type rest or basket in the normal position. The type rest 29 is

preferably a rigid segmental bar carrying a suitable pad 31 on which the forward or free ends of the type bars rest. From an inspection of Fig. 2 it will be seen that the links 26 are in the nature of parallel links and that the universal joints by which the links are connected to the segment, or to the arms 22 projecting therefrom, afford a movement of the type bar support in any direction and that the leaf springs 30 are sufficiently wide to afford a movement of the type bar support either to the right or left for a considerable distance without displacing the links from the springs.

The construction is such that the spring supported type bar support will absorb the shock of the type bars as they are restored to normal position no matter in what direction the impact is received from the type bars striking against the type bar support. It will be understood furthermore that the system of segmentally arranged type bars normally resting in the basket or against the type bar support, tends to maintain it in the normal position and that the shock or impact of a returning bar tends to displace the type bar support against the pressure of one or both of the springs 30, inasmuch as the impact is always received in a general downward direction. When one of the type bars at one side of the segment impacts against the type basket, the type bars at the other side of the system tend to prevent a material displacement of the type basket in the direction of the blow, although a downward movement of the type basket against the tension of one or both of the springs 30 may take place. Thus from an examination of Fig. 4, it will be seen that if the left-hand type bar shown in said figure impacts against the type bar support the type bars at the opposite side of the segment will tend to resist a movement of the type rest as a whole toward the left, but that a slight downward movement of the type bar rest against the tension of one or both of the springs 30 is effected by the impact of the returning type bar. An impact of the center type bars against the type bar support or rest will be equally distributed against the power of both springs 30, whereas the shock or the impact from the side bars may be taken up mainly by one of the springs at the side of the type rest where the blow is delivered.

Various changes may be made without departing from my invention.

What I claim as new and desire to secure by Letters Patent, is:—

1. A type rest for supporting the free end of a type bar, said rest being connected to its support by a universal joint.

2. A spring supported type rest connected to its carrier by a universal joint.

3. In a typewriting machine, the combination of a type rest, a plurality of universal joints for connecting said type rest to its carrier, and springs for supporting said rest in its normal position.

4. A type rest comprising a rigid member which supports a plurality of type bars, said rest being supported by springs.

5. In a typewriting machine, the combination of a system of type bars, a type rest for supporting the free ends of said type bars, swinging links connected to said type rest, and means for affording a resilient support for the type rest.

6. In a typewriting machine, the combination of a system of type bars, a type rest for supporting the free ends of said type bars, parallel links connected to said type rest, and springs for supporting the rest in normal position.

7. In a typewriting machine, the combination of a system of type bars, a type rest for supporting the free ends of said type bars, links connected to said type rest, and a universal joint connecting each of said links to its support.

8. In a typewriting machine, the combination of a system of type bars, a type rest for supporting the free ends of said type bars, parallel links connected to said type rest, universal joints for said links, and springs for supporting the rest in normal position.

9. In a typewriting machine, the combination of a rigid type rest, a pad carried by said type rest, parallel links connected to said type rest, universal joints connecting said links to their supports, and springs co-operating with said links to support the type rest in its normal position.

10. In a typewriting machine, the combination of a type bar segment, arms extending from said segment, a type rest, universal joints between said arms and type rest, and springs for supporting the type rest in normal position.

11. In a typewriting machine, the combination of a type bar segment, type bars carried by said segment, a type rest supporting the free ends of said type bars, arms extending from said segment, parallel links connected to said type rest, universal joints between said links and arms, and springs for supporting said type rest in its normal position.

12. In a typewriting machine, the combination of a system of forwardly extending upwardly and rearwardly striking type bars, a segment on which said type bars are mounted, a rigid type rest for supporting the entire system of type bars, forwardly

extending arms on said type bar segment, parallel links pivoted to said type rest, universal joints connecting said links to said arms, and springs for supporting said type rest in the normal position.

Signed at the borough of Manhattan, city of New York, in the county of New York,

and State of New York, this 6th day of December, A. D. 1910.

JACOB FELBEL.
